UNITED STATES PATENT OFFICE.

JOHN P. DORAU, OF HORICON, WISCONSIN.

IRONING TABLE.

Application filed December 26, 1925. Serial No. 77,741.

This invention relates to improvements in ironing boards, and more particularly to ironing boards of the folding type.

It is one of the objects of the present invention to provide an ironing board which may be easily and quickly folded to a closed position, in which position the board may be readily stored and will occupy a minimum amount of space.

19 A further object of the invention is to provide a folding ironing board having a foot latch, operable to unlock the board for folding.

15 A further object of the invention is to provide a folding ironing board in which the supporting legs may be securely locked in open position, so that they cannot accidentally close or provide an unsteady support.

20 A further object of the invention is to provide an ironing board which is of very simple construction, is strong and durable, and is well adapted for the purposes described.

With the above and other objects in view, 25 the invention consists of the improved folding ironing board, and its parts and combinations as set forth in the claims, and all equivalents thereof.

In the accompanying drawing in which 30 the same reference characters indicate the same parts in all of the views:

Fig. 1 is a side view of the ironing board in open position;

Fig. 2 is an inverted plan view thereof 35 with the parts folded;

Fig. 3 is an enlarged fragmentary sectional view of a leg to show a detail of construction;

Fig. 4 is an enlarged fragmentary detail 40 sectional view taken at the point of intersection of the legs in Fig. 1 and looking upwardly; and

Fig. 5 is a detail view taken on line 5—5 of Fig. 4.

45 Referring now more particularly to the drawing, it will appear that the numeral 5 indicates the ironing board or table proper, which may be of any suitable shape, but is preferably of rectangular form, except the front portion 5' which is tapered. A U-bracket 6 is secured to the undersurface of the board medially of its ends, and there-adjacent is a longer U-bracket 7. Another U-bracket 8 is secured to the undersurface 55 of one end portion of the board.

Pivottally secured to the U-bracket 6 is a

pair of downwardly diverging legs 9 having their upper end portions cut diagonally to bear flatly against the undersurface of the board when said legs are unfolded. Secured 60 to the medial portions of the legs 9, by means of bolts 10, are a pair of braces 11 whose upper ends are pivoted to the U-bracket 7. Said braces force the legs 9 outwardly, when unfolded, and increase the 65 divergence of said legs over the divergence in folded position, as will be more fully set forth.

A third leg 12, bifurcated at its upper 70 end portion, is pivotally secured to the end U-bracket 8, the arm portions 13 being mounted on a pivot bolt 14. The lower end portion of the leg 12 is formed with a notch 15.

A V-shaped rod or connecting member 16 has its free end portion pivotally mounted 75 on the bolts 10 adjacent the inner faces of the legs 9. The opposite end of the V-member 16 is looped as at 17, to receive and slidably move on the leg 12 and cooperating with the looped portion is a shank portion 80 17' having enlarged end portions engaged and held in position by portions of said looped portion, said member 17' forming a bottom portion for the loop.

Pivottally secured between the bolt 10 of 85 each leg 9 and the outer end of the pivot bolt 14 are a pair of link members 18 and 19, pivotally connected together, as at 20 which are adapted to be folded or extended with respect to each other, as shown and 90 serve to limit the movement of the leg 9.

Mounted on the upper face of the leg 12 95 is a transverse brace 21 having reduced end portions 22. When the leg 12 is unfolded, said brace 21 bears against the legs 9 to force them to unfolded position and the movement of said brace, and consequently the outward movement of the leg 12 is limited by pins 23 projecting from the medial 100 portions of the legs 9.

When the board is folded, all of the parts lie flatly against the undersurface of board 5, as shown in Fig. 2. In this position, the member 16 has moved inwardly on the leg 12 and the links 18 and 19 are folded with 105 respect to each other. To unfold the board, it is only necessary to move the leg 12 away from the board as far as possible, the looped portion 17 of the V or connecting member 16 riding outwardly on the leg 12, causing the 110 unfolding of the legs 9 and links 18 and 19. The reduced end portions of the brace 21 ride

along the legs 9 and cooperate with the braces 11 to cause a further divergence of the legs 9, and hold them firmly in open position. The board is locked in open position by forcing the shank portion 17' of the member 16 into the notch 15 of the leg 12, as shown in Fig. 1. To unlock the board, it is merely necessary to step on the portion 17 to disengage the shank portion from the notch, and then the parts may be readily folded, as indicated.

To prevent the legs from slipping on polished floors, the outer ends of the legs are provided with rubber caps or tips 25 which are formed with cups or holes 26 in order to create a suction when the legs bear against the floor.

From the foregoing description it will be seen that the improved ironing board is of very simple and novel construction, and is well adapted for the purposes set forth.

What I claim as my invention is:

1. An ironing table, comprising a board member, a pair of legs pivotally and non-slidably connected to the bottom portion thereof medially of its ends, a third leg pivotally connected to the bottom portion of the board at one end, said pair of legs and said third leg crossing each other medially of their length when moved away from the board, a connecting member connected to said pair of legs and movably and slidably associated with said third leg, and foldable links between an end portion of said board and said pair of legs.

2. An ironing table, comprising a board member, a pair of legs pivotally and non-slidably connected to the bottom portion thereof medially of its ends, a third leg pivotally connected to the bottom portion of the board at one end, said pair of legs and said third leg crossing each other medially of their length when moved away from the board but being medially unconnected, a connecting member connected to said pair of legs and exteriorly slidably engaging said

third leg, said third leg having a notch in its outer end portion to releasably engage said connecting member to lock the legs in open position, foldable links between an end portion of said board and said pair of legs, brace members secured to said pair of legs and pivoted to a medial portion of said board, and a transverse brace secured to said third leg for bearing engagement with said pair of legs.

3. An ironing table, comprising a board member, a pair of legs pivotally and non-slidably connected to the bottom portion thereof medially of its ends, a third leg pivotally connected to the bottom portion of the board at one end, said pair of legs and said third leg being crossed when moved away from the board, a connecting member connected to said pair of legs and slidably engaging said third leg, foldable links between an end portion of said board and said pair of legs, and brace members secured to and bearing against outer intermediate portions of said pair of legs and pivoted to a medial portion of said board.

4. An ironing table, comprising a board member, a pair of outwardly diverging legs pivotally connected to the bottom portion thereof, a third leg pivotally connected to the bottom portion of the board, said pair of legs and said third leg being crossed when moved away from the board, a pair of braces pivotally connected to the bottom portion of the board outwardly of the pivotal connections of said pair of legs, said braces being rigidly connected to intermediate outer portions of the pair of legs and exerting a pressure on the same when said legs are in unfolded position, and a connecting member pivotally connected with said pair of legs and slidably mounted on said third leg, said third leg having means for releasably locking said connecting member.

In testimony whereof, I affix my signature.

JOHN P. DORAU.
